APPARATUS FOR THE MANUFACTURE OF
CEMENTITIOUS SHEETS

René Dorn and Martin Willis, New Orleans, La.

Application April 28, 1932, Serial No. 607,971

14 Claims.

(Cl. 25—42)

This invention pertains generally to apparatus for the formation of sheets and particularly to apparatus for the formation of sheets from pulps.

In our copending application Serial No. 607,970, now Patent No. 2,004,935, dated June 18, 1935, there is shown and described a novel cementitious sheet and a process for making the same. The invention herein relates to apparatus adapted to be used in carrying out the aforementioned process.

Referring to the drawings in which like reference characters are appended to like parts in the various figures,

Figure 1 is an elevation of apparatus for carrying out the above-mentioned process;

Figure 2 is a plan view thereof;

Figure 3 is a perspective view of a matrix showing a layer of pulp thereon;

Figures 4, 5 and 6 are broken sections of finished sheets;

Figure 7 is an elevation partly in section of a hopper and of parts adjacent thereto;

Figure 8 is a plan view of the hopper, and

Figure 9 is a detail of an adjustable eccentric.

Referring more particularly to the drawings, at 10 in Figures 1 and 2 is shown a conveyor illustrated as being of the driven roller type. However, any other suitable type of conveyor, whether endless or not, may be substituted therefor.

Resting on the conveyor 10 is a matrix 11 having an upper surface 12 with a shape substantially identical with that of the sheet to be manufactured.

At 13 is shown a hopper containing pulp 14. Hopper 13 has an opening 15 transversely thereof of a length equal to the desired width of the layer 16 of pulp which is formed by pulp 14 passing through the opening 15. The hopper shown is of the type more particularly described and claimed in our co-pending application Serial No. 706,814, now Patent No. 2,004,936, dated June 18, 1935.

Pulp 14 may be of a consistency so as to flow by gravity through the opening 15 but is preferably of lesser water content. This will require some special means to cause the pulp to flow through the opening 15 because of the stiffer and viscous consistency. Such means may comprise a vibrating hopper, a form of which will be more particularly described hereinafter or any other suitable device such as one adapted to extrude the layer 16 through a die conforming to the desired opening 15 by means of pressure on the pulp 14 with or without heat.

If the pulp contains a fibre, such as pulp made from hydraulic cement, asbestos fibre and water, the fibre upon passing through the narrow opening 15 will become substantially oriented into planes more or less parallel with the surface of the layer 16 formed by the opening 15. We find substantial orientation is obtained with layers up to three quarters inch in thickness.

The matrix 11 is positioned and moved relative to the layer 16 so that the end of layer 16 contacts the right end of matrix 11 as seen in Figure 1, the matrix 11 preferably moving to the right on conveyor 10 at a speed conforming more or less closely to the speed at which the layer 16 issues from the opening 15 so that the layer 16 15 will be laid out on the matrix 11 without undue stretching or buckling.

The layer 16 will conform to the surface 12 of matrix 11 whether such surface 12 is flat, corrugated or of any other configuration, forming 20 thereon a sheet layer of substantially uniform cross sectional thickness throughout.

Depending upon the type of means employed for depositing layer 16, this layer may have a certain slight surface unevenness or waviness. 25 To remove any such irregularity, we may provide a roller 18 adapted to lightly touch the upper surface of the layer 16 throughout its width, the roller 18 having a contour conforming to that of the layer 16. The roller 18 preferably is driven 30 so that its surface moves oppositely to that of the layer 16 and at a substantially greater speed. The roller 18 is essentially a smoothing roller and its contact with the layer 16 should not be such as to cause pulp to accumulate on the front side 35 of the roller 18.

Any other means might be substituted for the roller 18 such as a shoe adapted to lightly contact the upper surface of the layer 16.

It might be pointed out here that it is not 40 necessary to expel any water from the layer 16 at this point. Expelling of water is accomplished by means of a press 25 having an upper matrix or die 26 conforming to the upper surface of the layer 16 and a lower matrix or die 27 for 45 holding the matrix 11. To expel water, matrix 27 together with the matrix 11 and the sheet thereon are raised by means of the piston and cylinder arrangement shown at 30, the upper surface of the layer 16 coming in contact with the 50 matrix 26 and being substantially uniformly contacted thereby throughout its surface so that the water is expelled without substantially disturbing the previous structural relationship of the sheet 16 or substantially displacing the par- 55

ticles of the layer 16 in a lateral sense and without setting up high pressure zones at irregular places throughout the area. The reduction in section will be small and uniform throughout 5 the layer 16.

The apparatus adapts itself very readily to the manufacture of laminated sheets, it being merely necessary to duplicate the hopper 13, as 10 illustrated at 21, or to add any additional number of hoppers depending upon the number of laminations desired. As shown, the roller 18 has been duplicated at 23.

Any additional layers such as the layer 20 deposited upon layers 16 will conform to the configuration of the layer 16 in all respects similarly 15 to the manner in which the layer 16 has conformed to the matrix 11. Due to the semi-fluid character of the layers of pulp and the care with which the second layer is deposited upon the first, 20 there may be a slight and inconsequential shift of material so that one layer might be very slightly thicker at one point than at another. However, such slight shift in material is wholly incidental and in no way departs from the spirit of the invention. 25

Orientation of the fibres greatly increases the tensile strength of the layer per unit of fibre content.

By variation of fibre content in each layer the 30 tensile strength across a section of a sheet may be varied in accordance with demands. For instance, if the load is on one face of the sheet the layer adjacent the load will be under compression and the layer opposite the load will be under 35 tension. The layer under compression may, therefore, have less fibre in view of the higher compressive strength of materials of this type. This will increase its resistance to the elements.

It is very simple to provide means for studying 40 the division line between the adhering laminations by merely providing any suitable device such as illustrated at 19 for depositing a thin film or stripes of coloring matter 17 on the layer 16 before application of the layer 20 thereto. We 45 find that a very suitable coloring substance can be made by mixing 90% dry hydraulic cement and 10% red iron oxide. It is, of course, understood that any other substance might be substituted therefor inasmuch as the function of this coloring 50 matter is merely to show the division line between the adhering laminations to identify the process by means of which the sheet has been manufactured. If more than two laminations comprise the sheet, it is, of course, understood 55 that, if desired, any additional number of color depositing devices may be added.

The manufacture of sheets by means of combining laminations affords an opportunity to 60 efficiently incorporate reinforcement members during the steps of superimposing the layers.

For instance, in the manufacture of corrugated sheets, particularly those used for roofing purposes wherein the vales are placed under tension and the crests under compression, inasmuch 65 as the compressive strength of this type of material is substantially greater than the tensile strength it is desirable to reinforce the vales. This may be done by laying longitudinal rods in the vales between the hoppers 13 and 21. These 70 longitudinal rods, of course, are not reshaped in the press 25 but already have the shape which they will have in the finished product. It is, of course, possible to also insert rods in the crests if desired or insert rods in the crests only. It is 75 also possible to employ any other form of rein-

forcement alone or in addition to the rods such as mesh of which wire cloth and expanded metal are examples. Such mesh would be preformed to conform to the upper surface of the layer 16 so that no reshaping would be necessary in the 5 press 25 or otherwise. For instance, if the sheet is to be corrugated, the mesh would also be corrugated.

After the desired number of laminations have 10 been superimposed with or without coloring matter and/or reinforcements, the composite mass is placed within the press 25 and the water expelled in the same manner as above set forth.

The matrix 11 is then withdrawn and the sheet 15 is stripped therefrom or permitted to cure on the matrix as desired.

While the invention has been described in connection with a single matrix, it is, of course, understood that the matrices 11 will succeed each other on the conveyor 10. In fact, the matrices 11 may be arranged on the conveyor 10 with abutting ends so that the layers of pulp may be deposited continuously, the cutting of the layers between the matrices 11 taking place just before introduction of each matrix into the press 25. 25

Other means may be substituted for the press 25 for expelling water from the sheets.

In Figure 3 we have shown a corrugated matrix 28 with perforations 29 to permit escape of water. However any other form of filter bed 30 may be substituted. It will be seen that the layer 31 has conformed to the corrugations.

In Figure 4 we have shown a sheet 32 comprising upper lamination 33 and lower lamination 34. The line 35 shows the colored dividing line 35 between the layers 33 and 34, the inclusion of which is, of course, optional.

In Figure 5 we have shown a sheet 37 comprising upper lamination 38 and lower lamination 39. 40 45 40 is the dividing line between the two laminations. At 41 we have shown rods positioned in the vales between laminations 38 and 39 for reinforcement purposes.

It is, of course, understood that the laminations join into a unitary sheet and strongly ad- 45 here to the reinforcing members 41.

In Figure 6 we have shown a sheet 43 comprising upper lamination 44 and lower lamination 45. We have also shown a corrugated reticular reinforcing member 46 positioned between the 50 laminations 44 and 45. The laminations, of course, adhere to each other and to the reinforcing member 46.

In Figures 7 and 8 we have shown a vibrating hopper. This hopper comprises oppositely arranged reciprocating side walls 50 and 51, shown arranged in the form of a V with an opening 52 at the vertex. Side walls 50 and 51 are shown arranged between stationary end walls 53, the side walls 50 and 51 being supported in guides 54 55 secured to the end walls 53.

Mounted on the frame 49 are two transverse shafts 56 and 57. Shaft 56 is shown driven by a motor 58 through reduction gearing 59 and belt or chain 60. Shaft 57 is illustrated as driven from shaft 56 by means of a chain 61.

Shaft 56 is journaled in slidable blocks 62, blocks 62 being adjustable by means of screws 63 to move the side wall 50 with respect to the side wall 51 to adjust the opening 52.

Shaft 57 is journaled in blocks 65 being adjustable by means of screws 66 for the purpose of moving side wall 51 with respect to side wall 50 to adjust the opening 52.

Side wall 50 is mounted on spaced eccentrics 55

67 in a manner so that the eccentrics 67 reciprocate side wall 50 upon revolution of the shaft 56.

Side wall 51 is mounted on eccentrics 68 on shaft 57 in a manner so that side wall 51 is reciprocated upon revolution of the shaft 57.

The reciprocation of the side wall 50 may be timed with respect to the reciprocation of side wall 51 by means of adjusting chain 61 on sprocket 71 on shaft 56 and on sprocket 72 on

10 shaft 57. The adjustment is preferable one in which side walls 50 and 51 reciprocate in unison, that is, synchronously. It is, of course, understood that the length of chain 61 will vary according to the adjustment at 63 and 66.

15 The variation in size of the opening 52 and the movement of the side walls 50 and 51 about the opening 52, due to the reciprocation of side walls 50 and 51 not only causes the pulp 73 to flow through the opening 52 in layer form but also tends to cause any fibre in the pulp to become oriented into planes substantially parallel to the surfaces of the layer of pulp formed at the opening 52.

20 As shown, the opening 52 has a longitudinal dimension more or less equal to the width of the matrix 11.

25 The cross sectional contour of the layer of pulp may be varied by variation in the lower edge of side wall 51 and/or side wall 50. This will prove of advantage in forming corrugated sheets with thickened crests and vales such as described and claimed in copending application Serial No. 447,150 of Martin Willis and Frederick Schroder.

30 Side wall 50 in Figure 7 is illustrated as being somewhat longer than the side wall 51 at the opening 52. The side wall 50 thus acts somewhat as a base toward which the side wall 51 may operate in the formation of a layer, both side walls acting to advance the layers through the opening 52. However, any other arrangement of the ends of side walls 50 and 51 may be made.

35 The layer 16, issuing from the opening 52, may be more or less undulatory in character in a lengthwise direction. If desired, a roller 75 may be provided for smoothing the layer 16. The action of roller 75 is merely smoothing in character and roller 75 ordinarily will no more than lightly touch the surface of the layer 16. Roller 75 preferably rotates in a direction opposite to the movement of the layer 16 on matrix 11 and should preferably have a somewhat increased peripheral speed. Roller 75 may be made adjustable vertically by means of screws 76.

40 The chute, shown at 77, pertains to a device for keeping the pulp 73 at a uniform height in the hopper and otherwise does not pertain to this invention.

45 Another means for timing the reciprocation of side wall 50 with respect to the reciprocation of side wall 51 is by use of an adjustable cam. Such a cam, however, is more useful for varying the length of the stroke of the reciprocating side walls. One form of adjustable cam is disclosed in Figure 9 in which an eccentric rim portion 78 is made adjustable with respect to an eccentric hub portion 79 mounted on a shaft 80. The adjustment may be accomplished by providing the hub portion 79 with a plurality of spaced grooves 81 which are adapted to cooperate with a complementary groove 82 in the rim portion 78 to form a key-way for a key 83. It is, of course, understood that any other form of adjustable cam may be employed. By moving rim portion 78 with respect to hub portion 79 the length of the stroke 50 of the side wall may be varied as will be under-

stood by persons skilled in the art. Any necessary adjustment as to synchronization may then be made by adjusting chain 61.

55 It is, of course, understood that any other means may be employed for driving shafts 56 and 57 and for connecting the shafts together so as to synchronize the movements of side walls 50 and 51.

60 The particular description herein has been merely for the purposes of illustration and many modifications and/or substitutions may be made in the parts particularly described without departing from the spirit of the invention. The claims herein are intended to be limited only by the prior art.

65 We claim:

1. Apparatus for forming a sheet from pulp comprising a rigid matrix having the contour and extent of the finished sheet, and means independent of said matrix for forming pulp into a 20 layer and applying said layer upon said matrix.

2. Apparatus for forming a sheet from pulp comprising a matrix in the form of the finished sheet movable in a substantially horizontal direction having an operative surface of corrugated 25 contour, and means for depositing a corrugated layer of pulp upon said matrix as said matrix moves past said means.

3. Apparatus for forming a sheet from pulp comprising a rigid matrix having the contour and 30 extent of the finished sheet and having an operative surface conforming to the desired shape of the sheet, and means independent of said matrix for forming pulp into a layer and depositing said layer upon said matrix.

35 4. Apparatus for forming a laminated sheet comprising a formed matrix having a contour conforming to the desired shape of the sheet, means independent of said matrix for forming pulp into a layer and depositing said layer upon 40 said matrix, and means for similarly depositing a second layer of pulp upon said first layer.

45 5. Apparatus for forming a laminated sheet comprising a formed matrix having a contour conforming to the desired shape of the sheet, 45 means independent of said matrix for forming pulp into a layer and depositing said layer upon said matrix, means for similarly depositing a second layer of pulp upon said first layer, and means for consolidating said first and second layers and 50 expressing water therefrom.

55 6. Apparatus for forming a sheet comprising a rigid matrix having the contour and extent of the finished sheet, a hopper spaced above said matrix, said hopper adapted to issue a layer of 55 pulp therefrom and deposit it upon said matrix, and means for moving said matrix relative to said hopper.

60 7. Apparatus for forming a laminated sheet comprising a formed matrix having the contour 60 and extent of the finished sheet, a plurality of spaced hoppers, means for moving said matrix consecutively under said hoppers, said hoppers adapted to successively issue layers of pulp therefrom and deposit it upon said matrix.

65 8. Apparatus for forming a laminated sheet comprising a rigid matrix, means independent of said matrix for forming pulp into a layer and depositing said layer upon said matrix, and means for smoothing the surface of said layer.

70 9. Apparatus for forming a sheet comprising a corrugated perforated matrix movable in a substantially horizontal direction, and means for depositing a corrugated layer of pulp upon said matrix as said matrix moves past said means.

10. Apparatus for forming a sheet comprising a rigid formed matrix having the contour and extent of the finished sheet, said matrix also having an upper surface of a shape desired in the sheet, means independent of said matrix for forming pulp into a layer and depositing said layer upon said matrix, and a press having a matrix of a shape desired in the sheet and adapted to receive said first mentioned matrix thereon and substantially uniformly compress said layer to express water therefrom and to consolidate said layer.
11. Apparatus for forming a laminated sheet comprising a rigid formed matrix having the contour and extent of the finished sheet, said matrix also having an upper surface of a shape desired in the sheet, means independent of said matrix for forming pulp into a plurality of layers and superimposing said layers upon said matrix, and a press having a matrix of a shape desired in the sheet and adapted to receive said first mentioned matrix thereon and substantially uniformly compress said superimposed layers to consolidate said layers and express water therefrom.
12. Apparatus for forming a sheet comprising a corrugated matrix-forming filter-bed, and means for depositing a corrugated layer of pulp upon said filter-bed.
13. Apparatus for forming a laminated sheet comprising a rigid formed matrix of filter-bed

construction having the contour and extent of the finished sheet and also having an operative surface of a shape desired in the sheet, means independent of said matrix for forming pulp into a plurality of layers and superimposing said layers upon said matrix, and a press having a matrix of a shape desired in the sheet and adapted to receive said first mentioned matrix thereon and substantially uniformly compress said superimposed layers to consolidate said layers and express water therefrom.

14. Apparatus for forming a laminated sheet comprising a rigid formed matrix of filter-bed construction having the contour and extent of the finished sheet and also having an operative surface of a shape desired in the sheet, means independent of said matrix for forming pulp into a plurality of layers and superimposing said layers upon said matrix, means for depositing coloring matter on said pulp and a press having a matrix with an operative surface of the shape desired in the sheet, said last mentioned surface adapted to receive said first named matrix thereon and cooperate with said first mentioned surface to substantially uniformly compress said superimposed layers to consolidate said layers and express water therefrom.

RENÉ DORN.
MARTIN WILLIS.
